UNITED STATES PATENT OFFICE.

ANDREW T. WANNENWETSCH, OF HAMBURG, NEW YORK.

REFUSE-RECEPTACLE HOLDER.

Application filed July 24, 1922. Serial No. 577,030.

To all whom it may concern:

Be it known that I, ANDREW T. WANNENWETSCH, a citizen of the United States, residing at Hamburg, in the county of Erie 5 and State of New York, have invented new and useful Improvements in Refuse-Receptacle Holders, of which the following is a specification.

This invention relates to means for supporting a refuse receptacle so that the same when not in use may be stowed away underneath the drain board of a kitchen sink or withdrawn from underneath the same when refuse is to be placed therein.

It is the purpose of this invention to provide simple, convenient and inexpensive means whereby a refuse receptacle may be thus mounted on the underside of a drain board or elsewhere.

In the accompanying drawings:

Figure 1 is a fragmentary perspective view of a drain board and sink equipped with my improved receptacle holder and showing the refuse receptacle swung out 25 into its receiving position. Figure 2 is a front elevation of the same, partly in section, and showing the refuse receptacle swung underneath the drain board. Figure 3 is a horizontal section taken on line 30 4-3, Fig. 2, looking downwardly. Figure 4 is a similar view taken on the same line, looking upwardly. Figures 5 and 6 are fragmentary vertical sections taken on lines 35 5-5 and 6-6, Fig. 3. Figure 7 is a fragmentary vertical transverse section showing suitable means for attaching the refuse receptacle holder to a drain board made of 40 cast metal. Figure 8 is a similar view showing a modified construction of the refuse receptacle holder.

Similar characters of reference indicate corresponding parts throughout the several views.

The construction shown in Figs. 1-4 is 45 designed more particularly for supporting a receptacle holder on a drain board or shelf 10 which is made of wood and has its tail or discharge end overhanging one of the end walls 11 of the sink 12 which latter 50 in this instance is made of cast metal.

In its general construction, this receptacle holder comprises a bracket mounted on the sink and drain board, a horizontally swinging carrier mounted on the bracket and adapted to support the refuse receptacle 13 which latter preferably consists of

a metal pail, and a lid pivotally mounted on the carrier and adapted to cover and uncover the top of the pail.

The bracket preferably comprises a horizontal longitudinal bar 14 which, in the construction shown in Figs. 1, 2 and 4 is secured to the underside of the wooden drain board adjacent to the front edge thereof by means of screws 15, and a retaining arm 60 16 extending transversely inward and lengthwise toward the sink and having its inner end arranged between the transverse end wall 11 of the sink and the underside 65 of the tail end of the drain board, thereby preventing the bracket from sagging or getting out of place and insuring maintenance of the refuse receptacle in its proper position regardless of the weight of its 70 contents.

The carrier comprises an annular band or ring 17 of metal which is provided on one side with a laterally projecting arm 18 which is pivoted to the underside of the bracket by an eye 19 arranged on the outer 80 end of the arm and turning on a pin 20 depending from the supporting bar 14 adjacent to one end thereof which pin has a head 21 at its lower end for confining the eye thereon. In the preferred form of 85 the ring 17, the same is split and its ends are spaced apart to form a locking notch or recess 22 therebetween, as shown in Fig. 3. The arm 18 and eye 19 are preferably constructed of a piece of band iron which 90 is doubled upon itself and has opposite ends constructed to form laterally projecting lugs 31 on this arm which are secured to the ends of the ring 17 by rivets 24, as shown or by other suitable means.

On this ring is detachably mounted a housing or casing which receives and encloses the refuse receptacle. This casing comprises a circular wall or body 25 adapted to pass down through the ring and having an external bead 26 at its upper edge which rests on said ring and a bottom 27 at its lower edge, and a lid 28 pivotally connected on one part of its rim by a hinge 29 with the upper edge of the wall 25, so 100 as to be capable of swinging into an open and closed position relative to the top of the body of the casing.

The refuse receptacle 13 is adapted to be arranged within this casing and may be 110 placed therein or removed therefrom preparatory to emptying the receptacle upon

raising the lid of the casing. The casing may be removed from the carrier, and the receptacle removed from the casing to permit of thoroughly cleansing the same.

5 Upon swinging the carrier together with the casing and receptacle from underneath the drain board, the receptacle is accessible for depositing refuse in the same and upon swinging these parts underneath the drain board, they are out of the way.

10 The carrier is preferably pivoted so close to the underside of the drain board that the lid of the casing must be closed in order to permit the casing to pass underneath the drain board and the same must be moved fully from underneath the drain board before the lid can be opened. The carrier for this purpose is preferably provided on its ring with a handle 30 whereby the same may 15 be manipulated.

15 The hinge connecting the body and lid of the casing should preferably be arranged on the rear side of these parts so as to render the interior of the same conveniently accessible from the front side. In order to insure retaining the casing always in this 20 position, the upper part of the body of the casing is provided with a laterally projecting locking pin 23 which engages removably with the locking notch 22 in the carrier ring, as shown in Figs. 3 and 6.

25 In order to assist in supporting the carrier and hold the casing close to the underside of the drain board when the casing, receptacle and carrier are swung underneath the drain board, a lifting device is provided consisting preferably of a hook arranged on the supporting bar and having an upright back 32 forming a stop which is engaged 30 by the arm of the carrier and limits the backward movement of the carrier underneath the drain board, and a lower inclined lug 33 which engages with the underside of this arm and serves to support the same 35 when the carrier is underneath the drain board, as shown in Fig. 2.

40 Means are provided for automatically opening the lid of the casing when swinging the latter forwardly from underneath the drain board and closing the same upon swinging the same backwardly underneath the drain board. The preferred means for opening the lid shown in the drawings consists of a spring 34 surrounding the pintle 45 of the hinge 29 and having its opposite ends connected with the body and lid of the receptacle, as shown in Figs. 3 and 5, this spring operating to raise said lid into an open position when the same swings for-

wardly clear of the drain board. The automatic closing of the lid is effected by a part on its upper side engaging with the supporting bar upon moving the lid rearwardly underneath the drain board, this part preferably consisting of a closing leaf spring 35 bowed upwardly and arranged across the top of the lid and secured at one end thereto in such a position that upon moving the lid rearwardly, the upwardly bowed part of the closing spring engages the supporting bar 70 and gradually shuts the lid over the body of the casing.

75 The several parts of this holder are so constructed that the same may be reversed in order to permit of using the same in connection with drain boards arranged either on the left or the right hand side of the sink.

80 In the case of a metal drain board 36 having a depending marginal flange 37, the supporting bar 14 of the bracket is provided with one or more clamps 38 for securing this bar to said flange, each of said clamps having an outer jaw 39 lined with felt and engaging the outer side of the drain board flange and an inner screw 40 engaging the 85 inner side of this flange, as shown in Fig. 7.

85 If desired, the body and bottom of the casing may be omitted in which instance the bead of the refuse receptacle rests directly on the ring of the carrier and the lid 42 is 90 connected with one leaf 41 of a hinge while the other leaf 43 of the latter is detachably seated in a vertical socket 44 on the supporting ring, as shown in Fig. 8.

95 This holder permits of readily disposing of kitchen refuse while engaged in cooking and storing the same in a space which ordinarily is not used for any other purpose. Furthermore, the same is so constructed that the refuse when stored is under cover so as 100 not to attract flies, and thus renders the device very desirable from a sanitary standpoint.

105 I claim as my invention:

A refuse receptacle holder comprising a bracket adapted to be mounted on the underside of a drain board, a carrier for supporting the refuse receptacle comprising a supporting arm pivoted on said bracket to swing horizontally and a ring arranged on the arm and adapted to receive said receptacle, and a stop on said bracket adapted to be engaged by said arm for limiting the rearward movement of said carrier and provided at its lower end with an inclined lug which is adapted to engage the underside of said arm and lift the carrier.

ANDREW T. WANNENWETSCH.
